UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 26, 1920. Serial No. 391,879.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to typewriting machines, and especially to tabulating mechanism therefor.

Heretofore, difficulty has been experienced in correctly locating the carriage in the selected denominational position, this being due to the fact that at one time the tabulating mechanism is operated to select a position in a succeeding column after an operated type-bar returns to its normal position, and that at another time the tabulating mechanism is operated before the return of the type-bar. This causes different relations to exist between the loose dog and the escapement wheel of the carriage-escapement mechanism at times when the tabulating mechanism is operated, which results in incorrectly positioning the carriage by one letter-space when the carriage-escapement mechanism is in an abnormal position.

To overcome this, it has been proposed to render the tabulating mechanism ineffective by locking it until the type-key, and consequently the escapement mechanism, has been restored to normal position. In such devices, the speed of the typist is retarded, which results from the fact that the tabulator keys are ineffective or out of use until the type-key returns to normal position.

An object of the present invention is to insure the correct positioning of the carriage without rendering the tabulating mechanism ineffective, so as not to interfere with the speed of the typist.

In carrying out the invention, there is provided means to insure the same relation between the escapement wheel and the dog-rocker, irrespective of the condition of the type-bar when a tabulator key is operated.

To this end, a connection may be made between the tabulating mechanism and the dog-rocker of the escapement mechanism to rock said dog-rocker, to move the loose dog out of engagement with the escapement wheel at each depression of a tabulator key.

Other features and advantages will hereinafter appear.

In the accompanying drawings, Figure 1 is a sectional side elevation taken near the middle of the machine, and showing the invention applied thereto.

Figure 2 is a skeleton diagrammatic view, 60 showing the tabulating mechanism operated to release the carriage and the dog-rocker operated to move the loose dog out of engagement with the escapement wheel.

Figure 3 is a detail front view of the escapement mechanism, showing the parts in their normal positions.

Figure 4 is a view similar to Figure 3, showing the parts in position when the upper end of the dog-rocker is operated. 65

The invention is herein shown as applied to an Underwood typewriting machine, in which character keys 10, when operated, depress key-levers 11 to rock bell-cranks 12 about a fulcrum rod 13, to swing the type-bars 14 upwardly and rearwardly about their pivot 15. The type-bars 14 are provided with types 16 to strike against the front side of a platen 17. The platen 17 is rotatably supported for line-spacing movements in a carriage 20, which travels back and forth on a front rail 21 and a rear rail 22 of the main frame 23. The carriage is urged from right to left for letter-feeding movements by a spring-drum 24 connected to the right-hand end of the carriage 20 by a strap 25. The letter-feeding movements of the carriage are effected by a universal bar 26 operated at each type-stroke by heels 27 on the type-bars. The heels 27 move the universal bar rearwardly against a return spring (not shown) to actuate a dog-rocker 28 to reciprocate a loose dog 30 and a fixed dog 31 between the teeth 32 of an escapement wheel 33, the latter having the usual one-way pawl-driving connection 34 with a pinion 35, which meshes with a feed-rack 36 pivotally mounted at 37 on the typewriter carriage. 70

The loose dog 30 is normally in engagement with one of the teeth 32 of the escapement wheel 33 (Figures 1 and 3), and is held, by the escapement wheel, against a fixed stop 38 on the dog-rocker 28 and against the tension of a spring 40. When the universal bar 26 is operated, the loose dog 30 moves out of engagement with the tooth 32, and the fixed dog 31 is brought into the path of the disengaged tooth 32 (Figures 2 and 4), while the loose dog is swung about its pivot 41, 100 105 110

by the spring 40, to the position in Figure 4, where it is arrested against a fixed stop 42. When the type-bar 14 returns, the universal bar 26 also returns and permits the dog-rocker 28 to be swung about its pivot 43 by the spring 40, which is diagonally disposed in the usual way, to have a lateral pull on the loose dog 30 and a forward pull on the dog-rocker 28. When the dog-rocker returns to normal position from the position indicated in Figure 4, the loose dog 30 is brought into the path of the next tooth 32 of the escapement wheel, while the fixed dog 31 moves out of engagement with the tooth previously engaged by the loose dog. As soon as the fixed dog 31 moves out of engagement with the escapement wheel, the carriage 20 is free to move until the loose dog 30 is arrested against the stop 38, as shown in Figure 3, thus effecting a letter-space movement of the carriage.

Tabulating mechanism, shown herein, may be like that disclosed in the patent to J. C. McLaughlin, No. 956,144 of April 26, 1910, and may comprise a plurality of denomination-selecting keys 44, each being provided with a key-lever 45 to be swung about a pivot 46, to raise a plunger 47, having at its upper end a denomination-stop 48, which is brought into the path of column-stops 50 adjustably mounted on a stop-bar 51, the latter being supported on the typewriter carriage 20. When a tabulator key 44 is operated, the carriage is released by means of a universal bar 52, engaged by any one of the plungers 47, to rock a shaft 53 and pull downwardly on a link 54, connected to an arm 55 extending from said shaft. The upper end of the link 54 is connected to a lever 56, which is swung about its pivot 57 to raise the feed-rack 36 out of mesh with the pinion 35, by means of a roller 58 mounted at the forward end of said lever. When the carriage is thus released, it is moved leftwardly by the spring-drum 24 until arrested in the selected position by the column-stop 50, and the operated denomination-stop or counter-stop 48.

Ordinarily the tabulator key is operated when the escapement devices are in their normal positions. In practice, it frequently happens that the typist, in rapidly operating the machine, actuates the tabulator key 44 before the type-key 10 returns to its normal position, and while the escapement devices, which are under the control of the type-keys, are in their operated positions. This results in incorrectly positioning the carriage 20 by one letter-space. To illustrate, let it be assumed that the last digit in a column is being typed and the typist, desiring to tabulate the carriage to the hundreds position of the next column, depresses the hundreds tabulator key before the type-key and the escapement devices return. The carriage, in-

stead of being arrested at the selected position, is stopped at tens position.

Whether the carriage is correctly or incorrectly positioned depends on the relation of the loose dog 30 to the escapement wheel at the time of release of the carriage, which, as previously explained, is accomplished by raising the feed-rack 36 out of mesh with the pinion 35. When the carriage is released under normal conditions, that is, when the dog-rocker occupies its normal position, the loose dog remains in engagement with the tooth 32 engaged thereby of the escapement wheel while the feed-rack 36 is out of engagement with the pinion 35. When the carriage is released under abnormal conditions, that is, when the dog-rocker is held in its operated position by the operated type-key while a tabulator key is being operated, the loose dog is out of engagement with the escapement wheel and in a position to engage the next succeeding tooth 32 of the escapement wheel; consequently, an added movement of one letter-space of the carriage is effected as the counter-stop 48 moves out of engagement with the column-stop 50 subsequently to the re-engagement of the feed-rack with the escapement pinion, thus causing an incorrect positioning of the carriage.

To guard against the incorrect positioning of the carriage, there is provided an upwardly-projecting arm 60 on the carriage-release rock-shaft 53, which is moved forwardly when a tabulator key is operated, and engages the rear face of the dog-rocker 28 below its pivot 43 (Figure 2), to swing the upper end of the dog-rocker rearwardly, to move the loose dog 30 of the escapement mechanism out of engagement with the escapement wheel 33, thus insuring that the same relation will exist between the loose dog and the escapement wheel at each tabulating operation, irrespective of the condition (effective or ineffective) of the type-key.

With this arrangement, the carriage always moves one space further when the loose dog 30 re-engages the escapement wheel than it would under ordinary conditions. Consequently, the stop-bar 51, which may be provided with a scale for setting the stops 50, may be set one letter-space in advance of the usual position so as to allow for the extra letter-space movement of the carriage during a tabulating operation.

It will be understood that, with this arrangement, the speed of the typist, in operating the machine, is not hindered.

Variations may be resorted to within the scope of the invention, and portions of the improvements may be used without others.

Having thus described my invention, I claim:

1. In a typewriting machine, the combination of a carriage, tabulating mechanism for

said carriage, type-keys, escapement mechanism actuatable by said type-keys, and means operable by said tabulating mechanism to actuate said escapement mechanism.

5 2. In a typewriting machine, the combination of a carriage, escapement mechanism for said carriage, said escapement mechanism comprising a dog-rocker, tabulating mechanism, and means operable by said tabulating mechanism to operate said dog-rocker.

10 3. In a typewriting machine, the combination of a carriage, type-keys, a dog-rocker having a fixed dog and a loose dog thereon, means to be engaged by the dogs to feed said carriage when the type-keys are operated, tabulating mechanism, and means operable by said tabulating mechanism to operate said dog-rocker to move the loose dog 15 out of engagement with the engaging means when the tabulating mechanism is operated.

15 4. In a typewriting machine, the combination of a carriage, type-keys, escapement mechanism comprising a fixed dog and a loose dog, means to be engaged by said dogs to feed said carriage when the type-keys are operated, tabulating mechanism, and means operable by said tabulating mechanism to cause the loose dog to bear the same relation 20 to the engaging means when the tabulating mechanism is operated as when a type-key is operated.

25 5. In a typewriting machine, the combination of a carriage, escapement mechanism for said carriage, type-keys to operate said escapement mechanism, tabulating mechanism for said carriage, carriage-releasing mechanism operable by said tabulating mechanism, and means operable by said tabulating mechanism through said carriage-releasing mechanism, for operating said escapement mechanism.

30 6. In a typewriting machine, the combination of a carriage, escapement mechanism for said carriage, said escapement mechanism comprising a dog-rocker, type-keys to operate said escapement mechanism, tabulating mechanism for said carriage, carriage-releasing mechanism operable by said tabulating mechanism, said carriage-releasing mechanism comprising a rock-shaft, and an

35 arm on said rock-shaft to actuate said dog-rocker when the carriage-releasing mechanism is operated.

7. In a typewriting machine, the combination of a carriage, type-keys, carriage-escapement mechanism operable by said type-keys, said escapement mechanism comprising a dog-rocker and a loose dog thereon, said loose dog being movable to an ineffective position by the type-keys, tabulating mechanism, carriage-releasing means operable by said tabulating mechanism, and means also operated by said carriage-releasing means to move the loose dog to its ineffective position.

40 8. In a typewriting machine, the combination of a carriage, carriage-escapement mechanism comprising two co-operating elements, namely, an escapement wheel and a loose dog normally in engagement with said escapement wheel, tabulating mechanism, means operable by said tabulating mechanism to release said carriage, and means operable by the tabulating mechanism through the carriage-releasing means, for moving one of said elements out of engagement with the other.

45 9. In a typewriting machine, the combination of a carriage, carriage-escapement mechanism comprising a loose dog, tabulating mechanism, means operable by the tabulating mechanism to release said carriage, and means operable by the tabulating mechanism through the carriage-releasing means, for actuating the loose dog.

50 10. In a typewriting machine, the combination of a carriage, escapement mechanism comprising an escapement wheel, a loose dog normally in engagement with said escapement wheel, carriage-releasing means operable by said tabulating mechanism, the carriage-releasing means comprising a rock-shaft, an arm on said rock-shaft, and means operable by said arm to move the loose dog out of engagement with the escapement wheel.

JOHN WALDHEIM.
